CLAIM

The new and ornamental design for a cosmetic applicator, as shown and described.

DESCRIPTION

FIG. 1 is a perspective view of a cosmetic applicator showing my new design;

FIG. 2 is a view in left side elevation of the cosmetic applicator of FIG. 1;

FIG. 3 is a view in right side elevation of the cosmetic applicator of FIG. 1;

FIG. 4 is a top plan view of the cosmetic applicator of FIG. 1; FIG. 5 is a bottom plan view of the cosmetic applicator of FIG. 1;

FIG. 6 is a view in front elevation of the cosmetic applicator of FIG. 1;

FIG. 7 is a view in rear elevation of the cosmetic applicator of FIG. 1; and,

FIG. 8 is a perspective view of the cosmetic applicator of FIG. 1 affixed to an applicator wand wherein the applicator wand is depicted with broken lines and does not form part of the invention.

The broken lines are shown for illustrative purposes only and form no part of the claimed design.
